UNITED STATES PATENT OFFICE.

LEWIS CARL, OF MOUNT CARMEL, PENNSYLVANIA.

BRAKE-SHOE.

SPECIFICATION forming part of Letters Patent No. 437,676, dated October 7, 1890.

Application filed March 15, 1890. Serial No. 344,045. (No model.)

To all whom it may concern:

Be it known that I, LEWIS CARL, a citizen of the United States, residing at Mount Carmel, in the county of Northumberland and 5 State of Pennsylvania, have invented certain new and useful Improvements in Brake-Shoes; and I do declare the following to be a full, clear, and exact description of the invention, such as will enable others skilled in the art 10 to which it appertains to make and use the same, reference being had to the accompanying drawings, and to the letters of reference marked thereon, which form a part of this specification.

15 The special object of the invention is to connect a brake-shoe and its head, so that they may be securely held together and yet easily detached from one another. The means by which I accomplish this, and which constitute my invention, will first be described 20 in connection with the drawings.

Figure 1 of the drawings is an elevation in perspective showing the brake-shoe and its holder fastened together. Fig. 2 is a detail 25 sectional view of the bottom of the brake head and shoe; and Fig. 3, a top view, in perspective, of the shoe alone.

In the drawings, A represents the brake-head, and B its shoe. On the under side of 30 the head A, I make the dovetailed groove a, to receive the corresponding tenon b on the shoe, and across the groove a make a rectan-

gular groove a'. In the latter a still deeper countersink a² is made to receive the nut or head of the bolt which fastens the shoe to the 35 head, and another cavity by which I form the shoulder a³, against which catches the free end of the rear pivoted detent b' on the shoe. As the head A is slid on the dovetail tenon b it presses the detent b' down on a spring b²; 40 but as soon as the shoulder a³ has passed the end of the detent the said spring lifts it until its end bears against the shoulder, when the shoe and head are securely locked together. When it is desired to separate them, a knife- 45 blade or equivalent is slipped in above the detent, which is then held down until the head is removed.

Having thus described all that is necessary to a full understanding of my invention, what 50 I claim as new, and desire to protect by Letters Patent, is—

The brake-head A, having the dovetailed groove a, cross-groove a', and shoulder a³, in combination with a shoe B, having the dove- 55 tail tenon b, pivoted detent b', and spring b², under the detent, as and for the purpose set forth.

In testimony whereof I affix my signature in presence of two witnesses.

LEWIS CARL.
